CLAIM

I claim the ornamental design for a fire pit, substantially as shown and described.

DESCRIPTION

FIG. 1 is first perspective view of a fire pit in accordance with a first embodiment thereof;

FIG. 2 is a second perspective view thereof;

FIG. 3 is a side view thereof;

FIG. 4 is an end view thereof;

FIG. 5 is a side view of the interlocking section shown separately for ease of illustration;

FIG. 6 is first perspective view of a fire pit in accordance with a second embodiment thereof;

FIG. 7 is a second perspective view thereof;

FIG. 8 is a side view thereof;

FIG. 9 is an end view thereof; and,

FIG. 10 is a side view of the interlocking section shown separately for ease of illustration.

1 Claim, 6 Drawing Sheets
